UNITED STATES PATENT OFFICE.

DAVID HJORTH, OF BRIDGEPORT, CONNECTICUT.

PULL-SOCKET.

1,360,218.

Specification of Letters Patent. Patented Nov. 23, 1920.

Application filed March 18, 1919. Serial No. 283,385.

To all whom it may concern:

Be it known that I, DAVID HJORTH, a citizen of the United States, and resident of Bridgeport, in the county of Fairfield 5 and State of Connecticut, have invented certain new and useful Improvements in Pull-Sockets, of which the following is a specification.

My invention relates to new and useful 10 improvements in electric switches and more particularly to what is commonly known as electric pull sockets.

The purpose of the invention is to simplify and generally improve the mechanism 15 of switches of the above character and to design a switch that may be made up largely of sheet metal parts and whereby it can be quickly and inexpensively assembled ready for use; to design the socket switch so that 20 each pull of the chain will serve to operate the armature in one direction or the other to alternately make and break the circuit contact.

The same reference characters will be 25 found to indicate like or corresponding parts in the several figures of the accompanying drawings forming a part of this specification, and of which,

Figure 1 shows a vertical sectional elevation of my improved form of electric pull socket switch, taken on line *a—a* of Fig. 2.

Fig. 2 is a top plan view of Fig. 1.

Fig. 3 shows a central vertical cross section taken on line *b—b* of Fig. 2.

Fig. 4 is a bottom plan view of Fig. 3.

Fig. 5 is a further bottom plan view with screw shell and insulating washer removed.

Fig. 6 is a detached side view of the switch mechanism as seen from the opposite side of 40 Fig. 1, the armature being in a different position.

Fig. 7 is a further side view similar to Fig. 6 except that the armature, operating slide and pawl, are in a forward position.

Fig. 8 is a sectional elevation of the housing illustrating one of the two positions the pawl assumes when the slide is returning to its normal position, and

Fig. 9 is a detached opposite side view of 50 the slide and pawl shown in Figs. 6 and 7.

Referring in detail to the characters of reference marked upon the drawings, 12 represents the insulative block having a pocket 13 therein which is open upon two 55 sides and the bottom to receive the switch

mechanism. It is further provided with recesses 14 and 15 to receive the binding posts, and also has several holes to accommodate screws for holding the parts in position as will later be more fully explained. An insulating washer 16 is fitted to the under side of the porcelain and the threaded shell 17 is attached to the block and against the washer and serves to support an incandescent lamp, not shown. Both the insulating washer 16 and the shell 17 have their central portions cut away to accommodate the yieldable contact member 18 which is positioned between the disk and the porcelain and has its depending yieldable end 70 portion disposed centrally of the holder for engagement with a lamp, not shown.

The side flanges 19 of the holder are fastened to the porcelain block by means of screws 20 and 21 both of which extend up 75 in the porcelain block to engage and support the screw shell and washer which insulates the shell from the terminal members. The screw 21 which engages one of the flanges of the shell extends through the 80 block and into the binding post 22 to support the same in the recess 14.

The yieldable terminal 23 which is formed integral with the contact 18 is secured to the block by the screw 20. This terminal, 85 together with the corresponding yieldable terminal 24, forms a socket between which the armature 25 is positioned to form the circuit through the lamp. The terminal 24 is connected to the member 26 by a screw 90 27 which secures the two to the porcelain. The upper end of this member 26 is positioned in the recess 15 and is provided with a binding screw 28 which serves for the attachment of one of the line wires, not shown. 95 So much of the construction already described is not materially different from the construction of switches now in use. The novelty of the device, as will be noted from the further description, resides more particularly in the switch mechanism proper, whereby the armature is quickly thrown in and out of engagement with the socket formed between the terminals.

This switch mechanism is formed, for the 105 most part, of sheet metal and consists of four pieces, aside from the several pivotal studs, spring and armature and, as will be seen, comprises a housing 29 having an upper and lower flange 30, each of which have 110

their edges disposed toward and in alignment with each other to form runways upon which the ways 31 of the slide 32 operate. Screws 33 positioned in the top of the porcelain block serve to engage the top flange 30 in a manner to support and hold the housing up tightly against the top wall of the pocket of the block in a way to properly position the mechanism therein.

10 The armature 25 is pivotally mounted upon a stud 34 that is secured to the back of the housing. A spring 35 serves to throw the armature in and out of contact with the terminals for the purpose of operating the switch. This spring is positioned upon a guide pin 36, the inner end of which is pivotally connected to a stud 37 on a rocker member 38 while the other end is slidably supported in a hole of an ear 39 formed 20 upon the end of the armature. One end of the spring is positioned against this ear and the other against the stud 37 so as to throw the free end of the armature from one position to another, as the rocker member is rocked and its stud 37 carried past the center. The amount of throw of the armature is limited by the stops 40 secured to the housing and against which the short end of the armature strikes when operated.

30 The rocker member 38 is pivoted upon the inside of the housing and between the upper and lower flanges, and aside from the resistance of the spring 35 is free to be turned from the position shown in Fig. 6 to that 35 shown in Figs. 7 and 8 by the action of the slide 32 and through the engagement of a pawl 41 mounted on a pin 42 carried by the slide. This rocker member carries two pins 43 and 44 upon the opposite end portions of its near side as shown in Figs. 6 and 8 which 40 are alternately engaged by the sockets 45 in the forward edge of the pawl 41, and whereby the rocker member is moved from one position to another. The slide is normally held in its retracted position as shown in Fig. 6 by means of a spring 46 secured to a pin 47 upon the housing and whose free end engages the pin 43 mounted in the slide. The pull chain 48 is guided through a sleeve 49 secured to the side of the porcelain block 45 and positioned in front of the slide. This chain is made fast to the lug 50 formed upon the free end of the pawl so that the pawl and slide may be drawn forward in line with the movement of the slide through the connection of the chain and pawl against the action of the spring 46. The line of draft of the chain is central, being guided by the sleeve 49, yet the pawl being pivotally connected with the slide, is free to swing slightly upon its pivot when engaging the near pin 44, see Fig. 6, upon the rocker member so that when the rocker member flops around its other pin 42 will 60 engage the top edge of the other side of the

pawl, leaving the pawl free to move back, see Fig. 8, past the pin 43 when the slide returns to its normal position. The rocker member is thus positioned so that with the next forward movement of the slide and pawl the other pin 43 will be engaged by the socket to throw the rocker member against its spring connection with the armature.

From the foregoing it will be seen that with each pull of the chain the slide and connected mechanism will be operated to either open or close the switch and that with each complete pull of the chain the slide and pawl return to their normal position and in readiness for a further operation.

Having thus described my invention, what I claim and desire to secure by Letters Patent, is—

1. In an electric pull socket block switch, 85 the combination of an insulative block formed with a pocket, a housing fixed within said pocket and having inwardly projecting flanges forming runways, a stud projecting outwardly from said housing, an armature pivotally mounted upon said stud and adapted to open and close a circuit, a rocker member pivotally mounted within the housing, a guide pin pivotally connected at one end to said rocker member and slidably supported at its opposite end by said armature, a spring carried by said guide pin and engaging said rocker member and armature, a slide member engaging said runways, a pawl carried by said slide member 90 and adapted to engage the rocker member, and a pull chain connected to said pawl.

2. In an electric pull socket block switch, 105 the combination of an insulative block formed with a pocket, a housing arranged within said pocket and having parallel runways, an armature pivotally mounted and arranged entirely outside the housing for opening and closing a circuit, a rocker member arranged within the housing and having 110 pins projecting therefrom, a guide pin pivotally engaging the rocker member and slidably engaging said armature, a spring mounted on said guide pin and engaging said armature and rocker member, a reciprocating slide member traveling on said runways, a pawl arranged between the slide member and the housing and carried by the said slide member for engagement with the pins on said rocker member, means for retaining said slide member in normal position, and a pull chain connected to said pawl.

3. In an electric pull socket block switch, 125 the combination of an insulative block formed with a pocket, a housing arranged within said pocket and having upper and lower aligned flanges forming runways, a stud projecting outwardly from said housing, an armature pivotally mounted on said 130

stud and having an inwardly projecting ear formed with an opening, a rocker member pivotally mounted within the housing, a guide pin pivotally carried by said rocker member and projecting through the ear of said armature, a spring carried by the said guide pin and engaging said rocker member and ear, a slide member formed with grooves for engagement with said runways, a pawl carried by said slide member and adapted

for engagement with said rocker member, and a pull chain engaging said pawl.

Signed at Bridgeport in the county of Fairfield and State of Connecticut this 14th day of March, A. D. 1919.

DAVID HJORTH.
